UNITED STATES PATENT OFFICE.

DUANE H. CHURCH, OF NEWTON, MASSACHUSETTS.

WATCH-PLATE DRILLING AND TAPPING MACHINE.

SPECIFICATION forming part of Letters Patent No. 595,044, dated December 7, 1897.

Application filed July 1, 1897. Serial No. 643,107. (No model.)

To all whom it may concern:

Be it known that I, DUANE H. CHURCH, of Newton, in the county of Middlesex and State of Massachusetts, have invented certain new and useful Improvements in Watch-Plate Drilling and Tapping Machines, of which the following is a specification.

The aim of this invention is to provide an organized mechanism by whose automatic operation blanks for foundation-plates of watch-movements can be provided with all the necessary holes and those of the holes requiring it supplied with screw-threads, thus displacing many separate machines heretofore considered necessary to do this work and providing for its complete performance by a single machine requiring but a single attendant. Aside from this advantage the automatic performance of all this work by a single machine insures absolute uniformity in the plates, and this is highly important in view of the fact that in the American system of watchmaking the parts are required to be interchangeable.

In the completed plate there are a great many holes, variously located, and some screw-threaded and some not, so that it will be readily appreciated that a very great number of operations are necessary to complete the plate, and the machine of my invention is necessarily more or less complicated; but its form, as exhibited in the accompanying drawings, is thoroughly practical as has been demonstrated by actual use.

Briefly stated, and preliminary to a more detailed description, the general arrangement of the machine is as follows: On a suitable base there are erected a number of standards, each of which supports the following instrumentalities—viz., first, a turret which is rotated step by step in a fixed bearing and carries a series of independently-rotatable and longitudinally-movable tool-carrying spindles; secondly, a spindle-driving shaft which is rotated in a fixed bearing and is moved longitudinally at stated intervals to engage a clutch member on its end with a complementary clutch member on a tool-carrying spindle; thirdly, a primary slide which is reciprocated horizontally in fixed guides on the standard; fourthly, a secondary slide which

is reciprocated in guides on the primary slide at right angles with the movement of the latter and is provided with a blank-holder and stop mechanism, as hereinafter described, 55 for automatically determining the extent of movement of each slide in one direction and stopping said movement at any desired point.

The reciprocating movements of the slides are caused by yielding pressure, preferably 60 through the agency of compressed air, as hereinbefore described, so that each slide can be arrested at any point in its movement. The blank-holder is given a compound movement by the said slides and is arranged so that 65 any part of a blank held by it can be brought into position to be acted on by the acting spindle in the turret, the automatic stop mechanism above referred to co-operating with the slides in locating different parts of 70 the blank successively over the said acting spindle.

The series of instrumentalities above referred to constitutes a section of the machine, which is made up of a series of sections, all 75 operating in substantially the same way, excepting in the matter of certain details hereinbefore noted. A description of the construction and operation of one section will therefore be sufficient for all, the chief difference 80 between the sections being in the tools carried by the spindles of the different turrets, each turret carrying a series of tools which differ from those carried by the other turrets.

The blank plates are stacked in a suitable 85 magazine and a swinging transfferer takes them therefrom one by one and conveys them to the first holder, wherein the plate is subjected to the operation of the various tools in the turret. A second transfferer is ar- 90 ranged to take the plate from the first holder and transfer it to the second holder, and a third transfferer is arranged to take the plate from the second holder to the third holder, and so on. The third transfferer is construct- 95 ed to reverse the plate as it conveys it between the holders. In the last section of the machine the spindle-driving shaft is alternately rotated in opposite directions for purposes of screw-threading. A final transfferer takes 100 the plate from the holder of this last section and stacks it in a suitable receiver.

In the drawings which accompany and form part of this specification there is illustrated a form of embodiment of the invention.

Figure 1 represents a top plan view of the complete machine. Fig. 2 represents a front elevation thereof. Fig. 3 represents a rear elevation of the same. Fig. 4 represents a top plan view, on an enlarged scale, of a portion of the machine at the left-hand or commencement end thereof. Fig. 5 represents an elevation of the left-hand end of the machine on the same scale as Fig. 4. Fig. 6 represents an elevation of the first section of the machine as viewed from the side opposite that seen in Fig. 5. Fig. 7 represents a cross-section taken on the line 7 7 of Fig. 6 and looking in the direction of the arrow crossing said line. Fig. 8 represents a fragmentary rear elevation of the first section of the machine. Fig. 9 represents a longitudinal sectional view of the second section of the machine, looking toward the right-hand end of the machine. Fig. 10 represents a similar view with the turret in elevation and one of its tools at work. Some of the parts seen in Fig. 9 are removed to disclose other parts behind them. Figs. 11, 12, and 13 represent details of the clutch devices between the tool-carrying spindles and the spindle-driving shaft. Fig. 14 represents an elevation of the plate-holder seen in Fig. 10, together with the third transferrer in a position to remove the plate from said holder. Fig. 15 shows a sectional detail of valve mechanism controlling a fluid-pressure clutch for the spindle-driving shaft. Fig. 16 represents a top plan view of the plate-holding portion of the first section of the machine, together with a portion of the first transferrer in position under the holder. Fig. 17 represents a front elevation of the parts appearing in Fig. 16. Fig. 18 represents a section taken on line 18 18 of Fig. 16. Fig. 19 represents a plan view of the plate-carrying portion of one of the transferrers with a plate therein. Fig. 20 represents a side elevation of the same. Fig. 21 represents a cross-section thereof on line 21 21 of Fig. 19, together with a portion of a plate-holder of one of the sections of the machine. Fig. 22 represents a cross-section on the line 22 22 of Fig. 19. Fig. 23 represents a longitudinal section on line 23 23 of Fig. 16. Fig. 24 represents a plan view of the second plate-holder and the head of the third transferrer. Fig. 25 represents a section on line 25 25 of Fig. 24. Fig. 26 represents a plan view of the third plate-holder and the third transferrer, the latter being reversed as compared with Fig. 24. Fig. 27 represents a section taken on line 27 27 of Fig. 26. Fig. 28 represents a cross-section taken on line 28 28 of Fig. 24. Fig. 29 represents a sectionalized front elevation of the first transferring mechanism and a portion of the magazine. Fig. 30 shows a sectionalized front elevation of the third transferring mechanism with portions of the second and third sections of the machine. Fig.

30^a shows a detail view hereinafter described. Fig. 31 shows a section of the third transferring mechanism, taken at right angles to the section in Fig. 30, together with a sectionalized side elevation of the third section of the machine. Figs. 32 and 33 represent plan views of the third transferrer-head in reversed positions. Figs. 34 and 35 represent sections taken, respectively, on lines 34 34, Fig. 32, and 35 35, Fig. 33. Fig. 36 shows a sectionalized rear elevation of the last section of the machine and adjacent parts. Fig. 37 shows a sectionalized plan view of the same. Figs. 37^a and 37^b show detail views, hereinafter referred to.

The letter *a* designates the base upon which all the mechanism is supported, and *b* the standards erected upon said base in a line longitudinally thereof. Each of said standards supports instrumentalities for acting upon a plate, constituting in themselves a drilling-machine, or, as I term it, a "drilling-section" of the entire machine shown. The construction and arrangement of parts in each section is much the same, and a detailed description of one of them will in a measure suffice for all.

In a suitable bearing *c* on the front of the standard *b* there is rotatively mounted a turret *c'*, (see Fig. 9,) bored longitudinally for the reception of a circular series of spindles *c*², having provisions at their upper ends for holding drilling-tools *c*³ and provided at their lower ends with clutch members *c*⁴. These spindles are longitudinally movable in the turret and are pressed downwardly by springs *c*⁵ and are also rotatable in the turret, being designed to be separately actuated by a driving spindle or shaft *c*⁶, journaled in brackets *c*⁷ on the standard *b* and longitudinally movable therein and provided at its upper end with a clutch member *c*⁸ for engagement with the corresponding clutch members on the tool-carrying spindles. The said clutch member *c*⁸ is preferably in the form of a sleeve, (see Fig. 11,) fitted to slide on the reduced upper end of the shaft and pressed outwardly by a spring *c*⁹. The turret *c'* is moved periodically and locked in different positions to bring its tool-spindles successively into alignment with the driving-spindle *c*⁶, and the latter is moved longitudinally into rotative engagement with the tool-spindle and by continued longitudinal movement and rotation causes the tool to drill a hole in the plate, which is held in position over the turret in a manner hereinafter described.

The periodical movement of the turret and the locking thereof, as above described, are effected by the following instrumentalities: The turret has fastened to it a circumferentially-grooved collar *d*, notched at a number of places in its periphery, as shown at *d*¹ in Figs. 37 and 37^a, to correspond with the tool-spindles, so that a latch *d*², by successively engaging the notches, will hold the turret in different positions with one or another of

the tool-spindles in alinement with the driving-spindle. This latch d^2 is pivoted to the turret-casing c and is pressed into engagement with the notched collar by a spring d^3 .

5 Below the collar d another collar d^4 , Fig. 9, loosely surrounds the turret and is formed with a wide flange d^5 , carrying a pivoted pawl d^6 , Fig. 37, pressed by a spring d^7 against the periphery of the notched collar and 10 adapted by engagement with the notches, Fig. 37^a, to establish rotative connection between the flange and the turret under one direction of movement of the former, but to slide over the periphery of the notched disk under the opposite direction of movement. There is also pivoted to the flange d^5 a latch-displacing piece d^8 , having a diamond-shaped head d^9 , Fig. 37^b, for engagement with a pin d^{10} on the latch. The said displacing-piece 15 is pressed by a spring d^{11} against the periphery of the notched collar, and in normal position of parts, as exhibited in Fig. 37, the front inclined side of the diamond-shaped head d^9 stands ready to displace the latch by 20 acting against the pin d^{10} . The flanged ring or collar has an oscillatory movement, as will be presently explained, and under what may be termed the "forward" direction of movement thereof the latch is displaced and the 25 diamond head passes the pin d^{10} , so that the latch may move into engagement with the next notch, as shown in Fig. 37^a. Upon the return movement the rear inclined side of the diamond head rides over the pin.

30 The flange d^5 has a portion of its periphery cut with gear-teeth d^{12} , which project into a cylinder d^{13} in the standard b and mesh with a rack d^{14} , extending between pistons d^{15} in said cylinder, the rack and the piston forming in effect a single piston adapted to be reciprocated in said cylinder to produce the oscillatory movement of the flanged collar hereinbefore referred to. The reciprocations of the said piston are effected by fluid-pressure, preferably compressed air, which is admitted alternately to opposite ends of the cylinder through ports d^{16} , which communicate by passages d^{17} with the interior or bore of a casing d^{18} of a slide-valve d^{19} . (See Fig. 10.)

35 The passages d^{17} enter the valve-casing one behind the other, as indicated in Figs. 10 and 37, and the valve has a passage or port d^{20} communicating with a supply-pipe d^{21} and adapted to register alternately with the passages d^{17} . The said valve also has an exhaust-passage d^{22} , adapted to register alternately with the said passages. In the normal position of parts, as exhibited in the figures just referred to, the valve is in its outward position, in which it is held by a spiral spring d^{23} , arranged behind it, and in this position of the valve its passage d^{20} registers with the passage d^{17} , leading to the right-hand end of the cylinder, and hence the piston is held at 40 the left-hand end of its movement. Inward movement of the valve, to admit compressed air to the left-hand end of the cylinder and

simultaneously exhaust the charge from the right-hand end, is effected by the following means: On a shaft z , extending the length of the machine, there is keyed a disk d^{24} , having a series of V-shaped projections or cams d^{25} at different distances apart. A lever d^{26} is pivoted at one end to a bracket d^{27} on the standard b and at its other or free end bears 45 against the end of the valve d^{19} , while intermediate of its ends it is formed with an arm d^{28} , carrying a roller d^{29} , in contact with the periphery of the cam-disk d^{24} . The shaft z is actuated from the main or driving shaft y , 50 Figs. 36 and 37, through a worm x on the latter, meshing with a worm-wheel w on the shaft z , and as the latter rotates the cam projections d^{25} on its disk d^{24} operate to shift the valve d^{19} at stated intervals through the medium of the parts above described. It will 55 be seen that the shifting of the valve back and forth results in the oscillatory motion of the toothed ring which surrounds the turret, the effect of which, as previously indicated, is to turn the turret and bring a new tool-spindle into line with the driving-spindle c^5 . The longitudinal movement of the said driving-spindle toward the tool-spindle is effected through the following-described means, (shown in 60 Figs. 9 and 10:.) A lever c^9 , pivoted intermediate of its length, engages at one end the lower end of the driving-spindle and at the other end is equipped with a pin c^{10} , which bears against the periphery of a disk c^{11} , keyed on the shaft z and formed with numerous and varying 65 cam projections c^{12} , which in the rotation of said disk act successively against the pin c^{10} and thereby operate the lever to move the driving-spindle upward. A spiral spring c^{13} (shown clearly in Fig. 9) encircles the said spindle between one of its bearings c^6 and a pulley c^{14} , affixed to it, the said spring thereby exerting itself to depress the spindle. The 70 said pulley c^{14} serves for rotating the driving-spindle, and to this end receives a band or belt c^{15} , which passes rearwardly to and around a pulley c^{16} , mounted upon a horizontal shaft c^{17} , one stretch of the band running over an obliquely-set sheave c^8 . (See Fig. 75 37.) The pulley c^{16} is itself an idler and may be driven in either direction, and to regulate its rotation automatically, so that the tool-spindle may be driven first in one direction and then in the opposite direction when 80 required—as, for example, in tapping or screw-threading—the following arrangement is adopted, (see Fig. 37:)

The pulley c^{16} is located between two other pulleys c^{18} and c^{19} , which are driven in opposite directions from a suitable source of power, and the said pulley c^{16} is formed on each side with a cone-shaped clutch member c^{20} for frictional engagement with correspondingly-formed recesses c^{21} in the pulleys c^{18} and c^{19} . 85

The shaft c^{17} is mounted to slide in its bearings c^{22} and c^{23} , which project rearwardly from the supporting-bed a , and by reciprocating in its bearings said shaft carries the pulley c^{16} 90

alternately into frictional engagement with the pulleys c^{18} and c^{19} . This reciprocation of the shaft is accomplished through the agency of compressed air by the following-described 5 instrumentalities:

In one of the shaft-bearings c^{23} is formed a cylinder c^{24} , and the shaft carries a piston c^{25} in said cylinder. Referring now more 10 particularly to Fig. 15, c^{26} and c^{27} designate passages which communicate with opposite ends of said cylinder and at different points with a bore which is occupied by a slide-valve c^{28} , having supply and exhaust passages c^{29} and c^{30} for alternate communication 15 with the said passages c^{26} and c^{27} . The exhaust-passage c^{30} opens out of the top of the valve, while the supply-passage c^{29} communicates with another passage c^{31} , leading to a compressed-air-supply pipe c^{32} . A spiral 20 spring c^{33} , arranged under the valve, exerts itself to hold the same elevated, where its supply-passage communicates with one end of the cylinder and its exhaust-passage with the other.

25 The means employed to shift the valve and thereby reverse the direction of rotation of the tool-spindle are of the following description: A lever c^{34} bears at one end upon the upper end of the valve and at its opposite 30 end is pivoted to a bracket on the standard b , as shown at c^{35} , Fig. 6. Intermediate of its ends the said lever carries a pin c^{36} , bearing against the periphery of a disk c^{37} , keyed to the shaft z and formed with varied cam projections c^{38} to shift the lever, and consequently 35 the valve, by acting against the pin c^{36} .

Proceeding next to the work-holding devices, the letter f designates a primary slide which is mounted to move in a horizontal 40 plane lengthwise of the machine upon a guideway f' on the top of the standard b , and g designates a secondary slide arranged to move in a horizontal plane at right angles to the primary slide upon a guideway g' on the top 45 of the latter. This secondary slide carries at its forward end the work-holding means which overhang the turret, and it will here be seen that by adjustment of the two slides any desired position of the work with relation to the 50 tool which is to operate upon it can be had.

I shall next describe the means for automatically adjusting the slides, which include means for yieldingly impelling the slides and automatically-adjustable stop devices to determine the different positions of the slides.

55 Referring now more particularly to Fig. 7, the slideway f' for the primary slide is bored lengthwise to form a cylinder f^2 , in which fits a piston f^8 , fixedly connected by a screw f^4 60 with the primary slide, the said screw passing through a longitudinal slot in the slideway. Ports f^5 and f^6 at opposite ends of this cylinder communicate by separate passages f^7 and f^8 with the casing f^9 of a slide-valve f^{10} , 65 and the said valve has supply and exhaust passages f^{11} and f^{12} (see Fig. 31) for alternate

communication with the passages f^7 and f^8 . The other slideway g' (see Fig. 9) has a cylinder g'' , with ports g^2 and g^3 at opposite ends 70 communicating by properly-jointed passages g^4 and g^5 with the valve-casing f^9 , and the valve has supply and exhaust passages g^6 and g^7 to alternately register with the said passages g^4 and g^5 . There is a chest h on the lower side of the valve-casing in communication with a compressed-air pipe h' and having a number of ports f^{13} and g^8 for registry with the ports f^{11} and g^6 , respectively. 75

The position of the valve shown in the drawings, Fig. 31, is that which obtains when 80 compressed air moves the secondary slide rearwardly and the primary slide to the right. To cause movement of the slides in the opposite directions, the valve is shifted through the following means: A lever g^9 85 bears at one end against the outer end of the valve and at its other end carries a roller g^{10} in contact with the periphery of a disk g^{11} , keyed to the shaft z and formed with a series of cam projections g^{12} . The lever is pivoted 90 intermediate of its ends to a bracket 56 on the standard b , and the force of a spiral spring g^{14} behind the valve presses the pin g^{10} against the periphery of the disk g^{11} , so that the cam projections g^{12} may produce vibrations of the lever and the desired shifting 95 of the valve.

The stop devices hereinbefore referred to as determining the adjustment of the slides are of the following description: The primary 100 slide f is formed with a small lip or projection i , (seen clearly in Fig. 6,) which overhangs a disk i' , rotatively mounted on the side of the standard b , and said disk carries a circular series of studs or pins i^2 , projecting to various 105 extents from the disk and designed to severally coact with the projection or lip i on the slide. When the slide is moved from right to left by the fluid-pressure, its said lip by abutting against the particular stud or pin of said series which is directly in front of it determines an adjustment of the slide. The purpose of such adjustment having been accomplished and the slide returned to its right-hand position, the disk i' is shifted to bring 110 another of its pins in line with the lip by the following-described means: The said disk has a series of notches i^3 in its periphery corresponding in number and location with the pins, and there is a pawl i^4 , spring-pressed 115 against the said notched periphery and carried by a piston i^5 , to which it is pivotally connected, the said piston fitting a cylinder i^6 , bored in the standard b . Passages i^7 and i^8 , Fig. 7, establish communication between 120 opposite ends of the said cylinder and the passages f^7 and f^8 , respectively, which it will be remembered communicate with the cylinder f^2 . Through these channels compressed air is admitted alternately on opposite sides of 125 the piston i^5 , and thereby a reciprocation of the pawl i^4 produced to effect step-by-step 130

movement of the pin-equipped disk. A spring-catch i^9 by engaging the notches of the latter prevents its backward movement.

Upon the rear side of the slide f there is rotatively mounted a second notched disk j , having stop pins or studs j' similar to those in the disk i and designed for abutment of a lip j^2 , Fig. 36, on the secondary slide g when the latter is advanced by the fluid-pressure.

10 The notched periphery of said disk is engaged by a spring-pressed pawl j^3 , pivotally mounted on a piston j^4 , contained within a cylinder j^5 on the slide f . Communication for compressed air to said cylinder is established through passages j^6 and j^7 , extending between the opposite ends of the cylinder and the passages g^4 and g^5 , respectively, which, it will be remembered, communicate with the cylinder g^1 . Through these channels compressed air is admitted alternately on opposite sides of the piston j^4 and the pin-equipped disk moved step by step the same as the previously-described disk and with a like result.

15 It will be readily seen that by means of the above-described instrumentalities a great variety of positions of the work-holder can be established, and these many different positions are successively assumed by the holder through entirely automatic operation, as will 20 be apparent.

Having now described one of the drilling sections of the machine, I shall next proceed to describe the manner of transferring the work from the magazine to the first drilling section and from section to section, and also the specific means for holding the work.

The magazine which contains the blank plates is in the form of a tube k , Fig. 29, which is supported in a vertical position by a column k' , erected on the base a and to which it is securely clamped by a yoke k^2 , (see Fig. 4,) pivotally connected with the column, as shown at k^3 , so as to swing laterally, and provided with a clamping-screw k^4 to bear against the magazine and press the same into the concavity of the head k^5 on the column. The blank plates 2, Fig. 29, are stacked one upon another in the magazine, and spring-catches k^6 , fastened on the outer side of the magazine, project over its lower end, so as to take under the lowermost plate and thereby prevent the plates from dropping out. These catches are beveled on the lower side for a purpose which will presently appear.

55 The means for transferring the plates one by one from the magazine to the plate-holder of the first drilling-section are of the following description: A column m , erected on the base a , constitutes a bearing for an oscillatory and longitudinally-movable shaft m' , having affixed to its upper end and projecting at right angles thereto an arm m^2 , with an enlarged flat and rounded outer end supporting a cup-shaped plate-receiver m^3 , having a beveled rim to engage the beveled under sides of the catches k^6 and displace the same. The longitudinal movement of the shaft m' to

move the said plate-receiver toward the magazine is effected through the following-described agencies, reference being had more particularly to Figs. 29 and 31: Said shaft has a reduced lower end portion m^4 , which extends into a cylinder m^5 , fastened on the under side of the base a , and a piston m^6 fits said cylinder and is fastened to the shaft. 70

Passages m^7 and m^8 open into opposite ends of the said cylinder and communicate at different points with the bore of a casing m^9 , in which fits a slide-valve m^{10} , having supply and exhaust passages m^{11} and m^{12} for alternate registry with said passages m^7 and m^8 . On the rear side of the valve there are passages m^{13} , adapted for alternate registry with the valve-passage m^{11} and communicating with a compressed-air-supply pipe m^{14} . The 85 valve is normally depressed by a spiral spring m^{15} , inserted above it, and it will be seen that under this condition compressed air may charge the cylinder on the upper side of the piston while the exhaust is open on the lower 90 side of the piston. The valve is moved upwardly at stated intervals by means of a lever m^{16} , which bears at one end against the lower end of the valve and at the other carries a roller m^{17} in contact with the periphery of a disk m^{18} , keyed on a shaft v , which carries a worm-wheel u in mesh with the worm x . The said lever m^{16} is pivoted intermediate of its ends to a hanger m^{19} , depending from the base a , and the spring behind the 100 valve keeps the pin against the periphery of the disk m^{18} . While the regular portion of the periphery of said disk engages the pin, the valve remains in its normal position, above described. The disk, however, is formed with 105 a number of depressions or notches m^{20} , into which the pin passes periodically, thereby permitting the spring behind the valve to push the latter downwardly and open communication for compressed air to the under side of 110 the piston. The continued rotation of the disk restores the valve to its former position by reason of the side of the recess m^{20} acting as a cam against the pin m^{17} . By this means 115 it will be seen that reciprocations of the shaft m' may be produced at the times desired, and this reciprocation moves the plate-receiver m^3 toward and from the magazine to take the plates singly therefrom.

120 Rotary movement of the shaft to transfer the plate to the first drilling-section is effected through the following-described instrumentalities: A sleeve n loosely surrounds the shaft and is supported in a suitable bearing n' and has at its upper end a gear-wheel n^2 , 125 which is in mesh with a rack n^3 on a piston n^4 , fitting the interior of a cylinder n^5 . Said piston is reciprocated, in a manner presently to be described, to effect oscillations of the sleeve, and such oscillations are communicated to the shaft through the following-described means: The sleeve has fastened to it an arm n^6 , carrying a downwardly-projecting pin n^7 , which has a sliding engagement with

a slot n^8 in an arm n^9 , fastened to the shaft m' . Thus rotative engagement is established between the sleeve and the shaft, while provision is made for longitudinal movement of the shaft. The oscillatory movement is limited by means of adjustable screws n^{10} , (shown in Fig. 37,) against which the arm n^6 abuts.

The cylinder n^5 , hereinbefore referred to, has ports n^{11} and n^{12} at opposite ends, and 10 passages n^{13} and n^{14} extend from said ports to a valve-casing n^{15} , containing a slide-valve n^{16} , having supply and exhaust passages n^{17} and n^{18} for alternate registry with the said passages n^{13} and n^{14} . The supply-passage is 15 adapted to register alternately with passages n^{19} in communication with a compressed-air-supply pipe n^{20} . The valve is pressed downwardly by a spiral spring n^{21} , inserted behind it, and in its normal position, which is at the 20 limit of its downward movement, the valve establishes communication for compressed air to the cylinder on the left-hand side of the piston. The valve is shifted to establish communication for compressed air to the 25 right-hand side of the piston by the operation of a lever n^{22} , which is pivoted intermediate of its length to a hanger m^{19} and bears at one end against the lower end of the valve and at the opposite end carries a pin n^{23} in contact 30 with the periphery of a disk n^{24} , fast on the shaft v and having a cam projection n^{25} to displace the pin and lever and thereby shift the valve.

The construction of plate-transferring 35 means above described is employed not only for carrying the plates from the magazine, but also for conveying the plates between the different drilling-sections; but at one stage it is desirable to turn the plate over, and the following construction is employed to effect this 40 in the transferring of the plates between the second and third drilling-sections of the machine, reference being had more particularly to Figs. 30 and 31; the construction here 45 for raising and lowering the transerrer and for oscillating the same is that already described, but instead of simply fastening an arm, as m^2 , to the upper end of the shaft m' , I affix thereon a cylindrical head o , having an 50 elongated hub or sleeve o' , in which is journaled a shaft o^2 , carrying at its outer end a plate receiver and conveyer o^3 . The said shaft projects through the cylinder o , and has affixed to it therein a plate o^4 , which constitutes a piston adapted to oscillate between stops formed by the sides of a segmental block o^5 , secured in the cylinder, Fig. 55 31. An axial passage o^6 , bored in the shaft m' , communicates at its upper end with the cylinder o and at its lower end with a radial passage o^7 , which is adapted to register with a passage o^8 in the column m , which passage communicates with a compressed-air-supply pipe o^9 . By this means at a predetermined 60 point in the rotation of the shaft m' communication for compressed air to the cylinder o will be established, and this compressed air

impinging against the piston o^5 swings it over through an angle of one hundred and eighty degrees, thereby reversing the plate-receiver 70 o^3 . The plate o^4 is normally held against the stop o^5 by a coiled spring 25 , arranged in a recess 26 , formed in the cover 27 of the head o . (See Fig. 30^a.)

The specific construction of means for engaging and holding the plates in the transferring and drilling operations will next be described with reference first to Figs. 19, 20, and 21, which illustrate the construction of the plate-receiver of each transerrer except 80 the reversible one. As before explained, the plate-receiver is in the form of a cup with a beveled margin to engage the catches of the magazine. At diametrically opposite sides the receiver is recessed for the reception of 85 angular catches p , which are pivoted by pins p' , and have arms extending upward and formed with beveled projections at their upper ends overhanging the edge of the receiver, and other arms extending inwardly and 90 pressed downwardly by springs p^2 , as clearly shown in Fig. 21. When the said beveled catches come against the edge of the plate in the upward movement of the transerrer, the springs p^2 allow the catches to be displaced, 95 so that the said projections may pass the plate and snap over the same. At other diametrically opposite points the receiver is recessed, as shown at p^3 , for the accommodation of catches in the plate-holders of the 100 drilling-sections of the machine.

The plate-holder of the first drilling-section is shown in detail in Figs. 16, 17, 18, and 23 and comprises the following parts: A support q , fastened to the top of the secondary 105 slide g and projecting outwardly beyond the same and provided on its under side near the front with a bearing-piece q' , against which the plate is placed, and just back of this bearing-piece with a shoulder q^2 , against 110 which the edge of the plate is pressed; a clamp q^3 , pivoted to the support and arranged to press at its lower end against the edge of the plate; a rod q^4 , fitted to slide through a bore in the support and jointed at its front 115 end to the said clamp, a spiral spring q^5 being interposed between a head in the end of the rod and the rear end of a recess which contains the spring, the latter thus acting to press the lower end of the clamp against the 120 plate, and angular catches q^6 , pivoted in slots in the support and having arms extending downwardly and formed with beveled projections at their lower ends to take under the plate, and also having arms which extend laterally and are acted upon by spiral springs q^7 to press the lower ends of the catches inward.

The manner of introducing the plate into the holder above described is clearly illustrated in Fig. 18, where the transfer-arm is represented as moving upward and the catches are displaced by the action of the edges of the plate thereagainst.

The construction of the holders of the other drilling-sections is substantially the same as above described, except that there is no clamp such as q^3 . In each case there is a support r fastened to the secondary slide and having a bearing-piece r' containing pins which register with and enter holes in the piece being operated upon, said holes being made in the front section when piece was held by means shown for the plate to come against, and in each case this bearing-piece is recessed at diametrically opposite points, as shown at r^2 , to admit the catches of the transfer-arm, as illustrated in Fig. 21.

15 The construction of the plate-carrier of the reversible transfer-arm is necessarily modified as compared with the other transfer devices. It is illustrated in detail in Figs. 25, 27, 28, 32, 34, and 35 and is of the following 20 description: The plate-receiver o^3 hereinbefore referred to is in the form of a ring, which has interior recesses at diametrically opposite points, in which are pivoted catches s , as shown in Fig. 28, normally pressed toward the center of the ring by spiral springs s' , inserted behind them. The beveled upper ends of these catches slide past the plate when the receiver is moved toward the holder of the drilling-section and then snap over the 25 said plate, as shown in said Fig. 28. The catches of the holder are displaced by coming against inclined sides of recesses s^2 , formed in the ring, as clearly shown in Fig. 25, and the plate is received upon the rounded ends 30 of pins s^3 , Fig. 34, which are projected by spiral springs s^4 , inserted behind them, and are suitably confined by screws s^5 , entered through the ring at right angles to the pins and engaging grooves encircling the latter.

40 When the ring is turned over, as shown in Fig. 35, it will be seen that the plate does not change its position, but is still engaged by the spring-pressed pins and rests upon the catches s . Recesses t are made through the ring at 45 diametrically opposite points and open into the interior of the ring, as shown in Figs. 27, 32, and 33, and when the ring in its reversed position is moved toward the holder of a drilling-section these recesses receive the catches 50 of said holder, as clearly illustrated in Fig. 27, so that the edges of the plate may act against the beveled ends of said catches and displace the same and then snap under the plate, so as to retain it when the ring moves 55 away.

At the right-hand or completion end of the machine a receiving-tube 4 is supported similarly to the magazine at the other end of the machine, and it is of similar construction and 60 adapted to receive the plates as they are finished and transferred one by one from the final drilling-section.

The operation of the machine, briefly stated, is as follows: The magazine being charged 65 with a supply of blanks and the first transfer-arm standing normally under the same, by the operation of compressed air through

the medium described said transfer-arm rises, takes a plate from the magazine, lowers again, and then swings over to the first drilling-section of the machine. The stop mechanism for the slides of said section having been set and the slides impelled to their respective positions determined by said stop mechanisms, the transfer-arm rises to the plate-holder thus 70 positioned and the plate is introduced thereto, after which the transfer-arm lowers and swings back to the magazine. The proper tool-spindle having been brought into alignment with the driving-spindle by rotation of 75 the turret, the said driving-spindle rises, engages the tool-spindle, and rotates the same while advancing it upon the work, and thus a hole is drilled in the plate, after which the tool-spindle and driving-spindle lower. Then 80 the primary and secondary slides move, respectively, to the right and to the rear, the stop mechanisms are readjusted, and the said slides move, respectively, to the left and forward until limited by the stop mechanism, 85 and thus a different part of the plate is brought over the tool, whereupon the driving-spindle again rises and another hole is drilled. This continues until all the holes to be drilled by 90 this particular tool are completed, and then the turret is moved to bring a different tool into alignment with the driving-spindle and operations of positioning the plate again ensue, followed by operations of the tool newly brought to acting position. When all the 95 operations to be performed in this section of the machine are completed, the second transfer-arm swings under the plate, rises, and takes the plate, then lowers and swings over to the next drilling-section, where operations 100 similar to those pursued in the first section take place, and so the plate is carried through the machine and finally conveyed to the receiver-tube, where the plates are stacked as 105 they are finished. When the plate is transferred from the second to the third drilling-section, it is reversed by the turning over of the carrying-ring of the transfferer in the manner hereinbefore described, and thereafter the drilling operations are performed on 110 the reverse side of the plate to that treated in the first and second drilling-sections.

In the last drilling-section, or it may be in any other section where holes are screw-threaded, the driving-spindle is rotated first 115 in one direction and then in the opposite direction to withdraw the tool, as hereinbefore described.

The various air-pipes hereinbefore referred to are all coupled to a main air-pipe 3, and it 120 will be seen that when fluid-pressure is turned into the latter and the driving-shaft and pulleys set in motion the entire operation above described proceeds automatically.

In this machine more than one hundred operations are performed upon a plate in its passage through and a vast amount of labor is saved as compared with the methods heretofore pursued to accomplish the same result.

In all the sections the counter-shaft is either reversed in direction and slowed in rotation or slowed in the same direction during the time of the engagement and disengagement 5 of the clutches, as the clutches do not engage properly at the speed necessary to do the work on plates.

In the appended claims the adjustments or 10 positions automatically assumed by the work-holding means are referred to as "differential," because they result from movements thereof in different directions to different extents, which is made necessary from the fact that the many holes to be drilled in a plate 15 have no regularity or uniformity of relative location.

Having thus explained the nature of the invention and described a way of constructing and using the same, though without attempting 20 to set forth all of the forms in which it may be made or all of the modes of its use, I declare that what I claim is—

1. In a machine of the character described, the combination with a tool-spindle and means 25 for automatically operating the same, of work-holding means variously movable at right angles to the said spindle, and means for automatically establishing predetermined differential adjustments of said work-holding 30 means to successively present different irregularly-spaced portions of the work to the action of the tool.

2. In a machine of the character described, the combination with a tool-spindle and means 35 for intermittently operating the same; of a slide movable in a plane at right angles to the axis of said spindle; a second slide carried by the first slide and movable at right angles thereto, and having work-holding 40 means; and means for establishing predetermined differential positions of said slides to present different irregularly-spaced portions of the work to the action of the tool.

3. In a machine of the character described, 45 the combination with a tool-spindle and means for intermittently operating the same; of a slide movable in a plane at right angles to the axis of said spindle; a second slide carried by the first slide and movable at right 50 angles thereto, and having work-holding means; means for yieldingly impelling the said slides, and variable abutments to determine differential positions of the slides by 55 checking their movements under impulse of such yielding means for the purpose of presenting different irregularly-spaced portions of the work to the tool.

4. In a machine of the character described, the combination with a tool-spindle and means 60 for intermittently operating the same; of a slide movable in a plane at right angles to the axis of said spindle and having an abutment; a movable support having a series of abutments for coaction with that on the slide 65 and varying in extent of projection from their support; means for moving the latter step by step; a second slide carried by the

first slide and movable at right angles thereto and having work-holding means, said second slide also provided with an abutment; a movable support on the first slide, having a series of abutments for coaction with that on the second slide; means for moving said support step by step; and means for yieldingly impelling the slides. 75

5. In a machine of the character described, the combination with a tool-spindle and means for intermittently operating the same; of a slide movable in a plane at right angles to the axis of said spindle and having an abutment; a movable support having a series of abutments for coaction with that on the slide and varying in extent of projection from their support; means for moving the latter step by step; a second slide carried by the first slide 80 and movable at right angles thereto and having work-holding means, said second slide being also provided with an abutment; a movable support on the first slide, having a series of abutments for coaction with that on the second slide; means for moving said support step by step; and fluid-pressure apparatus for impelling said slides. 85

6. In a machine of the character described, the combination with a tool-spindle and means 90 for intermittently operating the same; of a slide movable in a plane at right angles to the axis of said spindle and having an abutment; a movable support having a series of abutments for coaction with that on the slide 95 and varying in extent of projection from their support; means for moving the latter step by step; a second slide carried by the first slide and movable at right angles thereto and having work-holding means, said second slide 100 also provided with an abutment; a movable support on the first slide, having a series of abutments for coaction with that on the second slide; means for moving said support step by step; fluid-pressure apparatus for impelling said slides; and means for automatically controlling the said fluid-pressure apparatus. 110

7. In a machine of the character described, the combination with a tool-spindle and means 115 for intermittently operating the same; of a slide movable in a plane at right angles to the axis of said spindle and having an abutment; a movable support having a series of abutments for coaction with that on the slide 120 and varying in extent of projection from their support; means for moving the latter step by step; a second slide carried by the first slide and movable at right angles thereto and having work-holding means, said second slide 125 also provided with an abutment; a movable support on the first slide, having a series of abutments for coaction with that on the second slide; means for moving said support step by step; and cam-controlled fluid-pressure apparatus for impelling the slides. 130

8. In a machine of the character described, the combination with a longitudinally-movable driving-spindle, a movable support, a

- series of tool-spindles rotatively and longitudinally movable therein, the said driving-spindle and tool-spindles having clutch members, means for shifting the movable support to bring its tool-spindles severally into alignment with the driving-spindle, and means for automatically moving the latter longitudinally; of work-holding means variously movable at right angles to the axes of the spindles, and means for automatically establishing predetermined adjustments of said work-holding means to successively present different portions of the work to the action of the tools.
15. In a machine of the character described, the combination with a longitudinally-movable driving-spindle, a movable support, a series of tool-spindles rotatively and longitudinally movable therein, the said driving-spindle and tool-spindles having clutch members, means for shifting the movable support to bring its tool-spindles severally into alignment with the driving-spindle, means for automatically reversing the directions of rotation of the latter, and means for automatically moving the same longitudinally; of work-holding means variously movable at right angles to the axes of the spindles, and means for automatically establishing predetermined 30 adjustments of said work-holding means to successively present different portions of the work to the action of the tools.
10. In a machine of the character described, the combination with a tool-spindle, and means for automatically operating the same with provisions for automatically reversing its direction of rotation; of work-holding means variously movable at right angles to the said spindle, and means for automatically establishing predetermined 35 adjustments of said work-holding means to successively present different portions of the work to the action of the tool.
11. In a machine of the character described, the combination with a longitudinally-movable driving-spindle, a rotary support, a series of tool-spindles rotatively and longitudinally movable therein, the said driving-spindle and tool-spindles having clutch members, means for automatically turning the support and locking it at different positions to align the tool-spindles severally with the driving-spindle, and means for automatically moving the latter longitudinally; of work-holding 45 means variously movable at right angles to the axes of the spindles, and means for automatically establishing predetermined adjustments of said work-holding means to successively present different portions of the work to the action of the tools.
12. In a machine of the character described, the combination with a tool-spindle and means for automatically operating the same, of work-holding means variously movable at right angles to the said spindle, a system of variable abutments and fluid-pressure apparatus 50 operating in conjunction with said abutments

to establish predetermined adjustments of said work-holding means for successively presenting different irregularly-spaced portions 70 of the work to the action of the tool.

13. In a machine of the character described, the combination with a tool-spindle, and fluid-controlled means for operating the same with provisions for reversing its direction of rotation; of work-holding means variously movable at right angles to the said spindle, and means for automatically establishing predetermined 75 adjustments of said work-holding means to successively present different portions 80 of the work to the action of the tool.

14. In a machine of the character described, the combination of a rotary support, a series of tool-spindles therein, an oscillating actuator having means of engagement with said support to turn it in one direction, a piston in gear with said actuator, and a cylinder enclosing the piston and having provisions for alternate inlet and egress of fluid-pressure on opposite sides of the piston.

15. In a machine of the character described, the combination of a rotary support; a series of tool-spindles therein; an automatic lock to determine different positions of the support; an oscillatory actuator having lock-displacing 95 means and means engaging the support for turning the same in one direction; a piston in gear with said actuator, and a cylinder enclosing the piston and having provisions for alternate inlet and egress of fluid-pressure on 100 opposite sides of the piston.

16. In a machine of the character described, the combination with a tool-spindle and means for intermittently operating the same; of a slide movable in a plane at right angles to the axis of said spindle, and having an abutment; a rotary support having a circular series of abutments for coaction with that on the slide and varying in extent of projection from the support; means for turning the latter step by step; a second slide carried by the first slide and movable at right angles thereto and having work-holding means said second slide also provided with an abutment; a rotary support in the first slide having a circular series of abutments for coaction with that on the second slide; means for turning said support step by step; and means for yieldingly impelling the slides.

17. In a machine of the character described, the combination with a tool-spindle and means for intermittently operating the same; of a slide movable in a plane at right angles to the axis of said spindle, and having an abutment; a movable support having a series of abutments for coaction with that on the slide and varying in extent of projection from their support; fluid-pressure means for moving said support step by step; a second slide carried by the first slide and movable at right angles thereto, and having work-holding means, said second slide also provided with an abutment; a movable support on the first slide having a series of abutments for coac-

tion with those on the second slide; fluid-pressure means for moving said support step by step; and means for yieldingly impelling the slides.

5 18. In a machine of the character described, a transferring mechanism comprising a longitudinally movable and oscillatory shaft carrying a work-holding arm, a piston on the shaft, a cylinder inclosing the piston with provisions for inlet and egress of fluid-pressure alternately on opposite sides of the piston, and means for oscillating the shaft.

15 19. In a machine of the character described, a transferring mechanism comprising a longitudinally movable and oscillatory shaft carrying a work-holding arm, a piston geared to the said shaft with provision for longitudinal movement thereof, a cylinder inclosing said piston with provisions for inlet and egress of fluid-pressure alternately on opposite sides of the piston, and means for longitudinally reciprocating the shaft.

25 20. In a machine of the character described, a transferring mechanism comprising a longitudinally movable and oscillatory shaft carrying a work-holding arm, a piston geared to the shaft with provision for longitudinal movement thereof, and a cylinder inclosing this piston with provisions for inlet and egress of fluid-pressure alternately on opposite sides thereof.

35 21. In a machine of the character described, a transferring mechanism comprising a longitudinally movable and oscillatory shaft carrying a transverse bearing and a cylinder with a fluid-pressure inlet, a work-holder journaled in said bearing and carrying an oscillatory piston in said cylinder, means for oscillating the shaft, and means for longitudinally reciprocating the same.

40 22. In a machine of the character described, a transferring mechanism comprising a longitudinally movable and oscillatory shaft carrying a transverse bearing and a cylinder and having an axial passage communicating with said cylinder and an elongated port opening out of the side of the shaft, a bearing for said shaft having a fluid-pressure-supply pas-

50 sage adapted to register with said port in various positions of longitudinal adjustment of the shaft, a work-holder journaled in the transverse bearing on the shaft and carrying an oscillatory piston in said cylinder, means for oscillating the shaft, and means for longitudinally reciprocating the same.

55 23. In a machine of the character described, the combination of a line of tool-spindles and means for intermittently driving and feeding the same, a series of work-holders with provisions for automatically establishing various predetermined positions of the work with respect to the tool-spindle, and reciprocatory work-transferrers for taking the work from one holder to another.

60 24. In a machine of the character described, the combination of a line of tool-spindles and means for intermittently driving and feeding the same, a series of work-holders with provisions for automatically establishing various predetermined differential positions of the work with respect to the tool-spindles, and work-transferrers for taking the work from one holder to another, one of said transferrers being automatically reversible, substantially as described.

65 25. In a machine for drilling watch-movement plates, the combination of a line of tool-spindles and means for driving and feeding the same; plate-holders automatically adjustable to establish various predetermined positions of the work with respect to the tool-spindles; a reciprocatory plate-transferrer arranged to automatically carry plates one by one from a magazine to one of the holders, and reciprocatory plate-transferrers operating automatically to carry the plates from one holder to another.

70 In testimony whereof I have signed my name to this specification, in the presence of two subscribing witnesses, this 21st day of June, A. D. 1897.
